UNITED STATES PATENT OFFICE.

CHARLES W. HAMEL, OF ST. LOUIS, MISSOURI.

GAME.

Application filed April 3, 1925. Serial No. 20,564.

This invention relates to new and useful improvements in games.

The objects of the invention are to provide a game consisting of a plurality of playing pieces divided into a series or groups, the pieces of each group being marked to distinguish them from the other groups and the playing pieces of each group being further marked in a predetermined correlation with each other.

Further objects of the invention are to mark and number each playing piece in a definite relation with the other playing pieces of its particular group, whereby one player can defeat or counteract the playing piece played by the opposing player by bringing forward a playing piece having a predetermined numerical value relative to the number of the playing piece of the opposing player.

With these and other objects in view, my invention consists in certain novel features of construction and arrangement of parts, hereinafter more fully described and claimed, and illustrated in the accompanying drawings, in which—

Figure 1 is a top plan view of the playing pieces comprising the game and arranged in random on a table in readiness for the players.

Figure 2 is a perspective detail view of one of the playing pieces.

Figure 3 is a perspective detail view of the same piece and showing the underside thereof.

Figures 4 to 9 are bottom plan views of the respective groups and showing the notations or marks contained on the bottom of the playing pieces.

Figure 10 is a plan view of a fielder's set which may be used in conjunction with the regular set.

Figure 11 is a perspective view of one of the fielder playing pieces.

Figure 12 is a perspective view of the same and showing the underside thereof.

Figure 13 is a bottom plan view of one group of the fielder set.

Figure 14 is a bottom plan view of the error group of the fielder set.

Figure 15 is an end elevational view of a modified form of a playing piece.

Figure 16 is a plan view of a scoreboard adapted to be used in conjunction with my game.

55

Figure 17 is a perspective detail view of a marker used with the scoreboard.

Figure 18 is a perspective detail view of another modified form of a playing piece.

The game consists of a plurality of playing pieces 10 which may be of any desired size and shape, in the drawings being shown as rectangular blocks, but, if desired, they could be circular shape or square and they could also be printed on heavy cardboard. 60 These playing pieces are divided into a number of groups or series, the pieces of each group being distinctively marked and preferably colored on the upper face and the sides as indicated at 11 so as to distinguish 70 the pieces of one group from the pieces of the other groups.

Where the game is intended to be used as a baseball game, one group 12 containing sixteen pieces is marked Pitcher group and is preferably colored black. Another group 14 containing sixteen pieces is marked Fair hit and is preferably colored brown. Another group 15 containing eight pieces is marked Foul hit and is preferably colored yellow. A group 16 containing six pieces is marked Umpire and is colored red. Another group 17 containing nine pieces is marked Runner and is colored blue, and a group 18 also containing six pieces is marked Call play and is colored green.

The undersides of all the pieces are white and are marked as at 19 to indicate various plays possible under the respective headings or groups as illustrated in Figures 4 to 9, 90 respectively, which show the undersides and markings of each playing piece, the latter being arranged in respective groups. Each piece also contains a number as indicated at X, said number being preferably arranged on each side of the marking 19. This number or denomination is selected with a definite relation to the numbers of the other pieces of the same group and also with respect to the other related groups and to the 95 plays, such piece is supposed to represent. Thus the particular difficulties and advantages of the particular play as encountered in an actual game are approximated as 100

closely as possible by the playing pieces which represent such plays.

It will be observed that the various playing pieces are colored, marked, and numbered as follows:

Pitcher—(sixteen pieces)—black.

Strike 1—5—11
Ball 2—6—10—16
Fair hit 4—8—12—14
Foul hit 3—7—9—13—15

Foul hit—(eight pieces)—yellow

Foul and strike 2—4—6—8
Foul and out 1—3—5—7

Fair hit—(sixteen pieces)—brown

1 Base hit 4—10
2 Base hit 8
3 Base hit 12
4 Home run 16
Out to first 1—5—15
Safe to first 2—6—14

See runner and umpire on batter to first
25 and for runner on base 3—7—9—11—13

Umpire—(six pieces)—red

Out 1—3—5
Safe 2—4—6

Runner—(nine pieces)—blue

First base runner to second base—out—1
First base runner to second base—safe—2
First base runner to second base—up-
35 pire—3

Second base runner to third base—out—5
Second base runner to third base—safe—4
Second base runner to third base—um-
pire—6
40 Third base runner to fourth base—out—7
Third base runner to fourth base—safe—8
Third base runner to fourth base—um-
pire—9

Call play—(six pieces)—green

Out 1—3—5
Safe 2—4—6

The purpose of these numbers is to enable one player to defeat or change the play of the opposing player to his own advantage. This is accomplished by utilizing the numerical mark of the playing pieces whereby the second player playing a piece of different denomination in predetermined relation to the piece played by the opposing or first player counteracts or defeats the play as called for by the piece of the opposing player. The players may play a piece one number above or below the number shown on the piece previously played and they can also combine the numbers of the various pieces of the particular group to enable said players to play a specific piece as will be described hereafter.

65 In playing the game, the playing pieces

are arranged on the table as shown in Figure 1, and each player, assuming there are two players, although any number can play the game, draws an equal number of playing pieces marked Pitcher, which represent the 70 plays originated by the pitcher. The number of pieces drawn by each player in the present instance may be either eight apiece, or they may draw four each and draw two additional playing pieces after each play. 75 The opposing sides are called ins, which are at bat and make the first play, and the outs, which play to the ins. The object of the outs is to strike out the batter and prevent him from scoring a fair hit and endeavor to make 80 him score a foul hit as the latter is liable to be an out or a foul strike.

The numbers on the reverse sides of the playing pieces are considered in contest plays so that when the ins play a fair hit or 85 a ball, the outs contest the same with a foul hit or a strike, respectively, it being understood that three strikes the batter is out and four balls the batter is safe at first. The score of strikes and balls on the batter is 90 determined by prior count but, if the final play ends on a fair hit, the count of strikes and balls is disregarded and the decision on the fair hit prevails, while for foul hit the count is held in abeyance until it is deter- 95 mined whether it was a foul strike or a foul and out. In the former case, a strike is counted against the batter provided it does not make the third strike, for strikes are not counted against the batter after the second strike. In the latter case, if it is a foul and out, the batter is out and the play will begin on the next batter. Three outs retires the side at bat and the outs will take their turn at bat and will be considered 100 as ins.

The outs in contesting the play may play pieces having one number below or above that played by the ins, providing only one playing piece is played. As an illustration: 110 If ins play #12 fair hit, then outs can play #13 foul hit, since a fair hit can be contested only by a foul hit and vice versa. But if ins should play #2 ball, then outs can play #1 strike and not a foul or fair 115 hit piece.

In addition to the above, outs are also permitted to add to or subtract from the number of the piece played in order to equal the number of a playing piece intended to be 120 played by the outs. Thus, should ins play #12 fair hit, outs can play #5 strike which added to 12 makes 17; also #11 strike, which subtracted from #17 equals 6; also #1 strike which added to 6 equals 7, and then play #7 foul hit. Every piece which is added or subtracted in the play must be played. In the present case, three strikes were played ending in a foul hit piece. Three strikes being out, it is unnecessary in 130

the present instance to determine decision on the foul hit because the batter is out, but had the count been one strike and three balls, then it would have been necessary to obtain 5 decision on the foul hit.

As another illustration, let us suppose outs play foul hit #13 of the pitcher group 12. Ins play fair hit #4, announcing it is to be added to the 13 which equals 17 and 10 then play foul hit #3, which subtracted from 17 equals 14, and then play fair hit #14. The score is now a ball and a strike. If the outs cannot play to reduce or prevent the fair hit as played, then the fair hit 15 stands and the players can draw four playing pieces from group 14 indexed fair hit. The outs must now play first and let us suppose that they place piece #15 marked out. The ins play piece #3 which is marked Runner 20 and umpire and the ins player announces that #3 is to be subtracted from 15, thereby making the remainder 12. Then he plays one base hit #4 which is subtracted from 12, thereby leaving 8, and then plays 25 the ending piece #8 which is a two base hit as given in group 14. Now if the outs cannot play a number under or above, nor figure out a combination of the numbers to offset the last piece played, the ins will be credited with a man on second base. But if the 30 outs are able to play piece #2 safe to first, which he announces is to be subtracted from the ending piece #8, thereby leaving 6, and then plays safe to first #6, the batter is safe 35 to first and the ins, instead of being credited with a two base hit, are reduced to a one base hit. If there are runners on bases, they cannot advance under the present instance because safe to first is to be considered as a 40 scratch hit, while on the two base hit play runners could have advanced an equal number of bases.

If, in the last mentioned case, the first base 45 is occupied, this would result in a force-off for which the umpire group must be consulted. The players, therefore, draw an equal number of playing pieces of group 16 marked Umpire and the outs will play first again. Supposing the outs draw pieces 50 numbered 1, 2, and 5, and then plays piece #1 which is out. The ins play piece #3 which, added to 1, makes 4, and plays piece #4 safe. The outs can now play piece #5 out which is one number above 4 and the ins 55 can then play the next number 6 safe. This would indicate that the force-off runner from first base is safe to second.

If a call play is intended, each side will 60 draw an equal number of call playing pieces, but the intended play must be announced and fully explained before drawing the pieces.

If the ending piece in playing the pitcher 65 group calls for foul hit and the opposing side is unable to prevent the play, then each

player draws four playing pieces from group 17 marked Foul hit and the method of play is the same as in playing the umpire pieces, the ins trying to end the play with a piece marked Safe and the outs endeavoring 70 to end the game with a piece marked Out. When a play is made on a piece marked Runner and umpire as in fair hit group, the runner group is first played to determine the fate of the batter and the umpire group 75 is then played.

In playing the game, each player must make a play, but if the ins player is unable to play, the outs player wins that particular play. Otherwise the players can continue 80 to play until all the playing pieces of that particular group are drawn or until one player is forced to pass, and thereby accepts the play last made.

Figure 10 shows a group of eighteen playing pieces 20 which may be used in conjunction with the playing pieces hereinbefore mentioned. These playing pieces 20 are preferably colored orange and are marked on their upper faces Infield and outfield, there being six outfield pieces and twelve pieces marked Infield. They are divided into two groups, groups 21 and 22.

The pieces of group 21 are provided on their undersides with the following inscriptions:

Pitcher #1	
Catcher #2	
First base #3	
Second base #4	100
Short stop #5	
Third base #6	
Left field #7	
Center field #8	
In field #9.	105

Pieces 1 to 6, respectively, are the infield pieces, pieces 7 to 9 are the outfield pieces. The pieces of group 22 are marked similarly to pieces shown in group 21 but the underside of each piece is provided, in addition to the usual mark, with the word error.

This fielder set is used when it is desired to keep score to find out who fielded the ball. In case of a safe hit consisting of one or more bases, whereupon the batter and runner on base advance the same number of bases, the play will be considered a hit to the outfield and, if it is desired to ascertain who made the play, the outfield pieces will 115 be consulted. In case a scratch hit is made, the batter succeeded in reaching first base by a narrow margin. This would, therefore indicate an infield hit and the infielder pieces are consulted to ascertain who fielded the ball.

In Figure 15 is shown an end elevational view of a modified form of one of the playing pieces in which the body portion 24 is provided on the opposite sides with chan-

nels or depressed portions 25 in which are received strips 26 containing the playing indicating marks.

Figure 17 shows a score-board consisting of a board member 27 provided with a group of sets 28 indicating the base portions of a base-ball diamond and is provided at one side with seats 29 to indicate the strikes and on the opposite side with a group of apertures or seats 30 indicating balls. Another group of seats 31 is used to indicate outs. A marker 32 provided with a reduced portion or shank 32^a is adapted to be seated in any one of the openings formed in board 27 to indicate the position of the runner on the diamond and to indicate the strikes, balls, and outs of the game, there being a suitable number of marks 32 provided for this purpose.

Figure 18 shows a modified form of playing piece the same consisting of a card 34 provided at its ends with oppositely disposed play indicating marks 35, the intermediate space 36 being left blank and may be used either to show a picture of the particular player in action or may be used for advertising purposes.

The pitcher set 12 is the main playing set and the other sets are merely used in contested plays. When the contested play has been determined by means of one of the appropriate supplemental sets 14 to 18, respectively, the play with set 12 is resumed. After the playing pieces 12 have been all used up by the players, they are mixed together again and the players draw new pieces and continue the play.

While it is preferable to have the ins play first, it is optional and the outs can play first if so desired.

While the game is illustrated as applied to baseball, it is equally as well adaptable for playing golf or other games.

I claim:

1. In a game, a plurality of playing pieces arranged in groups representing a certain phase of the game and each piece of each group being marked to indicate a certain stage of the game under said particular group, the markings of each piece being in predetermined relation with the markings of the other pieces of said group.

2. In a game, a plurality of playing pieces distinctively marked to separate said pieces in series of correlated groups indicating various stages of the game, each piece being provided with interrelated play determining marks whereby the pieces of each group can be placed against each other to determine the particular play.

3. In a game, a plurality of playing pieces distinctively marked to separate said pieces into series of correlated groups for indicating various stages of the game, each piece being provided with other marks normally

hidden from the player's view, the marking of each piece having predetermined relation with the markings of the other pieces of the same group whereby said pieces can be played against each other to determine the playing movement of the particular group.

4. A game comprising a plurality of playing pieces divided into groups denoting various stages of the game, the pieces of each group being distinctively colored or marked to distinguish them from the pieces of the other group and each piece being marked on the underside to indicate a particular play possible under the group to which said piece belongs, each being numbered to enable grouping of said pieces for playing such pieces against the number of the piece played.

5. A game comprising a plurality of playing pieces divided into groups denoting various stages of the game, the pieces of each group being distinctively colored or marked to distinguish them from the pieces of the other groups, each piece being marked on the underside to indicate a particular play possible under the group to which said piece belongs, the play indicating marks on the underside of each piece being arranged in correlation with the marks of the other pieces of the particular group whereby said pieces can be played against each other.

6. A game comprising a plurality of playing pieces divided into groups denoting various stages of the game, the pieces being distinctively marked according to their groups, each piece being marked on one face to indicate a particular play of the respective group and each piece being further provided with numbers whereby said pieces can be played in accordance with their respective numbers.

7. A game comprising a plurality of playing pieces divided into groups, denoting various stages of the game, the pieces being distinctively marked according to their groups, each piece being marked on one face to indicate a particular play of the respective group, and each piece being further provided with a numerical mark whereby pieces of each group can be played in a predetermined relation with each other in accordance with their numerical values.

8. A game comprising a plurality of cards provided near their ends with group marks dividing said cards into groups, each representing a certain stage of the game, each card being further provided adjacent to each group mark with a play indicating mark, the last mentioned marks being interrelated whereby one card or combination thereof can be played against another card.

9. A game comprising a plurality of cards provided at their ends with oppositely disposed group marks dividing said cards

into groups representing certain stages of said game, each card being provided adjacent to each group mark with a play indicating mark and with a number, the numbers of each card being arranged in a predetermined order with the playing marks and numbers of the other cards of that particular group whereby a card or combination there-

of can be played against the card played by the opposing player by adding or subtracting the numbers of said cards in a definite order relative to the number of said opposing card. ¹⁰

In testimony whereof I hereunto affix my signature this 31st day of March, 1925.

CHARLES W. HAMEL.
